YARN-LAYING MECHANISM FOR
KNITTING MACHINESJoseph L. Beers, Bloomfield, N. J., assignor to
Julius Kayser & Co., New York, N. Y., a corpora-
tion of New York

Application November 3, 1933, Serial No. 696,473

30 Claims. (Cl. 66—127)

This invention relates to straight bar knitting machines and more particularly to machines for the manufacture of full-fashioned stockings, and to multiple yarn-laying mechanism for successively laying or feeding a plurality of yarns in regular predetermined sequence.

My improved yarn-laying mechanism may be employed for the laying of yarns of different weights, materials, colors, or characteristics, for the purpose of producing course-wise stripes or rings, but the mechanism is primarily intended for use in laying a plurality of similar yarns in such manner that unavoidable irregularities in one of the yarns will be distributed in the knitted fabric so that—particularly in the case of lightweight pure silk stockings—light and heavy streaks or rings are avoided.

The primary object of the invention resides in the incorporation, in a unitary mechanism, of an operating device for selectively operating the carrier bars in predetermined, repeated sequence, in combination with a locking device for locking the carrier bars selectively in accordance with the predetermined sequence of operation thereof by said operating device.

An object of the invention resides in the direct association and connection of the locking device with the drive mechanism for the carrier bars whereby the two are operated in unison and in proper timed relation so as to positively prevent improper operation and locking of the carrier bars.

One object of my invention is to provide improved mechanism whereby three (or other desirable number) of separate yarns are fed to the bank of needles, and whereby a plurality of yarn carriers—preferably three—are so manipulated that the separate yarns are fed to the needles automatically in regular sequence, and so that the loops of succeeding courses are so engaged with each other that the yarn forming each course has its needle loops engaging the sinker loops formed by another yarn, and has its sinker loops engaging the needle loops formed by still another yarn, in such manner as to disperse, distribute, or conceal in the knitted fabric any irregularity that might otherwise have been produced by the looping together in adjacent courses of the needle and sinker loops of a single yarn of a thickness greater or less than the yarn thickness predominating in the fabric.

A further object of my invention is to provide a simple, rugged and effective mechanism whereby three (or other suitable number) of yarn-

carriers are each moved in one direction in turn, and brought to rest accurately in its proper position after such movement.

Still another object of my invention is to provide simple and effective brake mechanism whereby each of the yarn-carriers is accurately brought to rest on the completion of its yarn-laying movement.

A feature of the invention resides in the use of a novel type of clutch cooperating with the friction rod of the knitting machine for the accurate operation of the yarn carrier rods and their proper locking against the usual stops.

Another feature of the invention resides in the direct relating of the brake with the driving mechanism and the friction rod and friction box associated therewith, whereby the frictional action of the brake is applied just before the frictional pressure of the carrier rod against the narrowing head stop is released, thereby firmly and frictionally holding the carrier in position to prevent rebounds.

The invention is further distinguished in the use of a locking device that is mounted independent of the narrowing head and is not subject to the rebounds or vibratory actions of the narrowing head, thereby eliminating the possibility of broken needles, sharpened sinkers, cut ends and poor selvedges.

The invention is further distinguished in the use of a carrier operating mechanism that is in permanent engagement with all the carrier bars for their instantaneous operation, thereby eliminating the necessity of disengaging the mechanism from one carrier bar and engaging another carrier bar before travel can be imparted to the carrier bar.

With these and other objects in view my invention consists in the novel construction and arrangement of parts hereinafter described, illustrated in the accompanying drawings and particularly pointed out in the appended claims, it being understood that various changes may be made in the construction, arrangement, and operation without departing from the spirit of the invention or sacrificing any of the advantages thereof.

In the drawings, Fig. 1 is a side view of the improved yarn-laying mechanism, with parts of the knitting machine shown in cross section;

Fig. 2 is a diagrammatic view showing the cam means for the engagement of the yarn-laying mechanism;

Fig. 3 is a similar view showing the cam mechanism for the braking means;

- Fig. 4 is a cross-sectional view taken on the line 4—4 of Fig. 5;
 Fig. 5 is a plan view of the mechanism;
 Fig. 6 is a front view of the same;
 Fig. 7 is an elevation showing the "main friction" and "friction bar" of the machine; and
 Fig. 8 is a detail plan view, partly in section, showing the means for operating the mechanism from the main friction.
- The mechanism shown in the drawings is equipped for the laying of three separate yarns or threads which are laid in regular sequence, the first thread being laid as its carrier moves to the left, the second thread being laid as its carrier moves to the right, the third thread being laid as its carrier then moves to the left; and the first mentioned thread being again laid as its carrier moved to the right, and so on, without any one carrier making more than one stroke each time it is brought into operation.
- The mechanism is operated from the main cam shaft 10 (Fig. 1) of the machine by a cam 11 that engages a roller 12 on an arm 13 pivoted at 14 on a bracket 15 mounted on a portion 16 of the usual frame of the knitting machine. The roller 12 is moved away from the shaft 10 by the action of the cam 11 and the return movement is effected by means of a spring 17 anchored to a suitable part of the machine. A shogging movement of the cam shaft 10—at the proper time—brings a member 18 into engagement with the roller 12 so that the cam mechanism remains inactive until such time as the shaft 10 is again shogged to bring the cam 11 back into engagement with the roller 12.
- Secured to the arm 13 is a second arm 19 which is connected to and operates—through the medium of a connecting rod 20—an arm 21 pivotally mounted on one of the shafts (the "fashioning shaft") 22 at the rear of the machine. The arm 21 carries a pawl 23 that engages the teeth of a ratchet wheel 24 that is secured by means of pins 25 (Fig. 6) to a cam sleeve 26 all mounted on the said shaft 22 and these parts 21, 24 and 26 may be each formed in two longitudinal sections adapted for convenient assembly upon the shaft 22 as shown for example at Fig. 6 in the case of the arm 21 which is shown with its sections connected together by means of screws 27.
- The yarn-laying mechanism is mounted above and is controlled by the said cam sleeve 26 in the manner hereinafter described. A supporting bar 28 is suitably mounted on fixed portions of the framework of the knitting machine and carries a bracket 29 which is secured thereto by means of screws 30 and mounted on the bar 28 between the bracket 29 and a guide member 31 is a longitudinally movable toothed rack 32 that is automatically reciprocated in timed relation to the operation of the machine through the medium of the usual friction bar 33 and main friction 34 (Fig. 7) actuated in the usual manner from the "Couller" mechanism of the machine. The said friction 34 is provided in the usual manner with pivoted fingers 35 adapted to be swung into or out of operative position for the actuation of the usual carrier rods in the well-known manner. As shown at Fig. 7 the main friction 34 also carries a member 36 having a projecting end 37 that engages a recess in one side face of the said rack 32 (see Fig. 8, the rack being held in engagement with the member 36 by means of a set screw 38), and in this manner the movement of the friction rod

33 is transmitted to the rack 32 which latter in turn actuates three toothed pinions 39 for the actuation of the three thread-carriers embodied in this improved attachment. Each of the three wheels 39 is freely mounted upon a sleeve 40 carried on a shaft 41 which latter is mounted in ball-bearings 42 so as to rotate freely in the said bracket 29 carried on the bar 28. Each wheel 39 is connected by pins 43 to one member 44 of a toothed clutch whose cooperating member 45 is mounted upon the said sleeve 40 so as to rotate freely thereon and so as to move axially into and out of clutching engagement with the member 44. Secured to one end of each shaft 41 is an externally grooved brake pulley 47 which latter is secured to the shaft by means of a screw pin 46. Secured to each clutch member 45 and extending through the adjacent brake pulley 47 are three guide pins 48 adapted to slide freely through the said pulley as the clutch is engaged or disengaged; and mounted on the ends of the pins 48 is a disc 50 secured by nuts 49, while a coil spring 51 is held in compression between said disc 50 and the pulley 47, so that the clutch member 45 is normally held out of engagement with its cooperating member 44. The operation of the clutch 44, 45 is effected by means of a lever arm 52 pivotally mounted in a bracket 53 on the said bar 28, the upper end of the lever 52 being provided with an adjustable screw pin 54 adapted to engage a spring 55 mounted on the said disc 50, so that the clutch member 45 may be moved toward the clutch member 44 and the spring 55 provides a cushion to permit movement of the lever 52 although the teeth of the clutch members are not in position to immediately engage each other. The lower end of each of the three levers 52 is provided with a roll 56 for engagement with the clutch operating cams 57 hereinafter described.

Each of the brake pulleys 47 cooperates with a brake device comprising an arcuate brake shoe 58 and a friction member 59 for engagement with the groove of the brake pulley. Each brake shoe 58 is carried upon a pin or plunger 60 mounted in a sleeve or socket 61 adapted to slide vertically in a bracket 62 on the bar 28. The lower extremity of the sleeve or socket 61 carries a roll 63 for engagement with the brake actuating cams 64 hereinafter described, the brake actuating cams 64 hereinafter described, the brake device is normally pressed downward by means of a spring 65 in compression between the said bracket 62 and a shoulder 66 on the member 61. An internal spring 67 is interposed between the bottom of the socket in the member 61 and the lower extremity of the plunger 60 so as to provide a cushioning effect in the braking action; and a pin 68 on the member 60 traverses a slot in the socket 61 and a slot 69 (Fig. 1) in the said bracket 62 so as to limit the relative movement between these parts.

While each of the shafts 41 carries a brake pulley 47 on one of its ends, its opposite end carries a toothed pinion 70 which meshes with and actuates a toothed rack 71 which latter has a pair of depending lugs 72 to which is secured, by means of two pins 73, one of the usual carrier rods 74 of the machine and each rack 71 has also secured thereto a thread-carrier arm 75 of any suitable or well known type. The carrier rods 74 are supported and guided in the machine in the usual well known manner and the thread carriers 75 are arranged at suitable positions so

as to lay the threads in the desired manner. As shown at Figs. 4 and 5, the three racks 71 are arranged side by side and three pinions 70 are located above their respective racks, and the arrangement is such that the actuation of the rack 32 from the main friction 34 of the machine rotates all the pinions 39, but the clutch members are so actuated that only one of the three pinions 39 imparts its rotary motion to the corresponding pinion 70, so that one of the racks 71 is actuated in synchronism with the rack 32 while the remaining racks 71 remain stationary.

For the actuation of the clutches 44, 45 and 15 of the brakes 59 the rolls 56 and 63 are actuated from the cam sleeve 26 hereinbefore referred to. This cam sleeve 26 is actuated with a step-by-step motion in proper timed relation to the operation of the machine, and carries a 20 set of cams 57 for actuating each of the rolls 56 to swing the levers 52 against the action of the springs 51 to engage the clutches. The sleeve 26 also carries three sets of cams 64 for engagement with the rolls 63, the cams 64 of each set 25 being spaced from each other to permit disengagement of the brakes at the proper times under the action of the spring 65. As clearly shown in the diagrammatic views, Figs. 2 and 3, the cam members 57 for each roller 56 are 30 spaced at 90° apart, see Fig. 2; while the cams 64 for the rolls 63 are similarly spaced, see Fig. 3, and the arrangement of the cams relatively to each other is such that while one clutch is in engagement the corresponding brake is disengaged. In these diagrammatic views the full 35 lines indicate the cams 57 and cams 64 in their respective positions for one of the thread-carriers, while the dotted lines 57', 64' show the relative positions of the cams for the next carrier, and the dot-and-dash lines 57'', 64'' indicate the relative positions of the cams for the third carrier. It will thus be seen that a movement of the cam sleeve 26 through 30° will cause 40 one pair of rollers 56, 63 to disengage a clutch and apply a corresponding brake and will cause another pair of rollers to engage a clutch and 45 disengage a corresponding brake, and in this manner the said carriers are actuated in proper sequence so that one stroke is imparted to each 50 carrier in turn and at the completion of each stroke of a carrier its corresponding brake is applied to ensure proper stoppage of the mechanism, and the relative positions of the cams 57, 64 are preferably such that each brake is applied with increasing friction while its corresponding clutch is being disengaged or just before such disengagement, so that there is no 55 free movement of the carrier mechanism.

In concluding, attention is called to the fact 60 that the brake device and the yarn carrier bar operating elements are assembled and connected in a unitary structure so that the operation of the brake device and the yarn carrier bar operating elements will be positive and in proper timed relation to assure proper and full movement of the carrier bars and their positive locking at the end of their stroke so as to prevent broken needles, sharpened sinkers, cut ends, and poor selvedges. The yarn carrier bar operating elements and the brake devices are combined in 65 a unitary structure mounted stationarily upon the knitting machine in relation to the travel of the carrier bars so that the same will not be subject to rebound, which is characteristic of locking devices that are mounted upon the narrowing 70 75

heads of a full fashioned hosiery knitting machine. By operating the invention directly from the main friction of the knitting machine, advantage is taken of the positive operation thereof. In the provision of the positive type of 5 clutch, proper and accurate operation of the carrier bars by the operating elements is assured.

Attention is called to the fact that the invention may be used solely as a braking and locking 10 device, being very active and positive in its operation, due to the novel manner of operating the same directly from the main cam shaft of the knitting machine.

Although the drawings and the above specification disclose the best mode in which I have contemplated embodying my invention, I desire to be in no way limited to the details of such disclosure, for in the further practical application of my invention many changes in form 20 and construction may be made as circumstances require or experience suggests without departing from the spirit of the invention within the scope of the appended claims.

What I claim is:

1. Yarn-laying mechanism for a straight bar hosiery machine having a main friction, comprising a group of arms carrying individual yarns, rotary means for imparting a yarn-laying movement to each arm, reciprocating means actuated by the "main friction" of the machine for imparting rotary movement to said rotary means, and selecting means for connecting the reciprocating and rotary means to impart movement to the said arms in sequence. 35

2. Yarn-laying mechanism for a straight bar hosiery machine having a main friction, comprising a reciprocating member actuated by the "main friction" of the machine, a plurality of rotary members actuated by said reciprocating member, a plurality of yarn-carriers, positive clutch members connecting said carriers with said rotary members, and means for selectively actuating said clutch members to cause transmission of the motion of each rotary member to 40 its yarn-carrier in turn. 45

3. Yarn-laying mechanism for a straight bar hosiery machine, comprising a plurality of rotary members, a yarn-laying member actuated by each rotary member, a reciprocating member 50 for the actuation of all said rotary members, and positive clutch and friction brake mechanism for imparting the movement of each one of said rotary members to a yarn-laying member and for retaining the other rotary members at rest, and means for selectively operating the clutch and brake mechanism to insure operation of the yarn-laying members in proper sequence. 55

4. Yarn-laying mechanism for straight bar hosiery machines, comprising rotary cam mechanism, a plurality of positive clutch and friction 60 brake devices actuated by said mechanism, rotary means cooperating with the clutch and brake devices, means for actuating said rotary means, and a plurality of yarn-carriers actuated thereby and in a sequence determined by the 65 actuation of the clutch and brake devices.

5. Yarn-laying mechanism for straight bar hosiery machines having "main frictions", comprising a rotary sleeve, a plurality of cams integral with said sleeve, a plurality of clutches and 70 brakes actuated thereby, a plurality of rotary members, reciprocating means for simultaneously actuating said rotary members from the "main friction" of the machine, a plurality of yarn-carriers actuated by said rotary members, 75

and means for ensuring actuation of each yarn-carrier in a sequence determined by the actuation of the clutches and brakes.

6. Yarn-laying mechanism for a straight bar hosiery machine having a main friction, comprising a group of yarn-carrying arms, rotary means for imparting a yarn-laying movement to said arms, reciprocating means connected to the "main friction" of the machine for imparting movement to said rotary means, selecting means for connecting the reciprocating and rotary means to impart movement to the said arms in sequence, and rotary friction brake mechanism for halting each yarn-carrying arm on the completion of its movement.

7. Yarn-laying mechanism for a straight bar hosiery machine having a "main friction", comprising a toothed reciprocating member, means connecting said member directly to the "main friction" of the machine, a plurality of rotary toothed members actuated by said reciprocating member, a plurality of yarn-carriers, clutch means connecting said carriers with said rotary members, and cam means for actuating said clutch means selectively to cause transmission of the motion of each rotary member to its yarn-carrier in turn.

8. Yarn-laying mechanism for a straight bar hosiery machine, comprising a plurality of yarn-carriers, rotary means for actuating said carriers in sequence, a bracket carrying said rotary means, friction brake mechanisms for holding each carrier stationary after completion of its yarn-laying movement, and cam means for selectively applying certain of said brake mechanisms.

9. Yarn-laying mechanism for a straight bar hosiery machine having a main friction, comprising a plurality of toothed rotary members, a yarn-laying member actuated by each rotary member, a toothed reciprocating member for the actuation of all said rotary members, means for the positive connection of said reciprocating member with the "main friction" of the machine, rotary clutch and brake mechanism for transmitting the movement of one of said rotary members to a yarn-laying member and for retaining the other yarn-laying members at rest, and cam means for selectively operating the clutch and brake mechanism to insure operation of the yarn-laying members in proper sequence.

10. Yarn-laying mechanism for a straight bar hosiery machine having a main friction, comprising a plurality of rotary members, a plurality of yarn-laying members actuated by the rotary members, reciprocating means connected to the "main friction" of the machine for actuating the rotary members, cam mechanism and means for imparting step-by-step motion to said cam mechanism for controlling the actuation of the rotary members from the reciprocating member to actuate the yarn-laying members in sequence.

11. Yarn-laying mechanism for straight bar hosiery machines, comprising rotary cam mechanism, means for imparting step-by-step motion thereto, a plurality of positive clutch and friction brake devices actuated by said mechanism, rotary means cooperating with the clutch and brake devices, a reciprocating rack for actuating said rotary means, and a plurality of thread-carriers actuated thereby and in a sequence determined by the actuation of the clutch and brake devices.

12. Yarn-laying mechanism for straight bar hosiery machines, comprising a plurality of sets of rotary cams, a plurality of positive rotary clutches and friction brakes successively actuated

by said cams, a plurality of rotary toothed members, a reciprocating rack for simultaneously operating said rotary members, a plurality of thread-carriers operated by said rotary members, and means for ensuring actuation of each thread-carrier in a sequence determined by the actuation of the clutches and brakes.

13. Yarn-laying mechanism for a straight bar hosiery machine having a main friction, comprising a group of yarn-carrying arms, a rack and pinion for imparting a yarn-laying movement to each arm, reciprocating means for imparting movement to said pinion, means for connecting said reciprocating means with the "main friction" of the machine and selecting means for connecting the reciprocating means with one of said pinions to impart movement to the said arms in sequence.

14. Yarn-laying mechanism for a straight bar hosiery machine, comprising a reciprocating member, a plurality of rotary members actuated by said reciprocating member, a plurality of racks and pinions, a yarn-carrier on each of said racks, positive clutch members connecting said pinions with said rotary members, and means for actuating said clutch members to cause transmission of the motion of each rotary member to its corresponding thread-carrier in turn.

15. Yarn-laying mechanism for a straight bar hosiery machine having a main friction, comprising a plurality of rotary members, yarn-laying means including a toothed rack actuated by each rotary member, a reciprocating toothed rack connected to the "main friction" of the machine for the actuation of all said rotary members, and a toothed clutch for imparting movement to each of the yarn-laying means, means for retaining the other rotary members at rest, and means for selectively operating the clutches to insure operation of the yarn-laying members in proper sequence.

16. Yarn-laying mechanism for a straight bar hosiery machine having a main friction, comprising a plurality of rotary members, a plurality of yarn-laying members actuated by the rotary members, reciprocating means connected to the "main friction" of the machine for actuating the rotary members, clutches for controlling the actuation of the rotary members from the reciprocating member to actuate the yarn-laying members in sequence, and spring and cam means for holding each clutch in turn in its operative position.

17. Yarn-laying mechanism for a straight bar hosiery machine having a main friction, comprising rotary cam mechanism, a plurality of toothed clutch and friction brake devices actuated by said cam mechanism, rotary means cooperating with the clutch and brake devices, reciprocating means directly attached to the "main friction" of the machine for actuating said rotary means, a plurality of thread-carriers actuated by said rotary means in a regular sequence determined by the actuation of the clutch and brake devices, and cam and ratchet means for operating said rotary cam mechanism.

18. Yarn laying mechanism for a straight bar hosiery machine having a main cam shaft and a main friction, comprising a plurality of yarn carriers, means for actuating said carriers in repeated sequence from the said main friction, and friction brake mechanism operated directly off said main cam shaft for holding each carrier in position after completion of its yarn laying movement.

19. Yarn laying mechanism for a straight bar hosiery machine including a main cam shaft and a main friction comprising a plurality of yarn carriers, means for actuating said carriers in repeated sequence from said main friction, a friction brake for each yarn carrier and operatively associated with said means for holding certain carriers in their position of rest during the yarn laying movement of an associated carrier, and cam and spring means operated directly off said main cam shaft for applying and releasing said brake. 5
20. In combination with the yarn carrier bars, main friction, and main cam shaft of a full fashioned hosiery knitting machine, actuating mechanism for said carrier bars comprising: means including a rack and pinion drive connection for each carrier bar operatively connected to said main friction and means operatively connected to said first means and operated directly off said main cam shaft for individually and selectively connecting the rack and pinion connection of each carrier bar with said friction bar. 10
21. In combination with the yarn carrier bars, friction rod, and main cam shaft of a full fashioned hosiery knitting machine, actuating mechanism for said carrier bars comprising: means for individually operating said carrier bars including a rack and pinion drive connection for each carrier bar and means operated directly off said main cam shaft for individually and selectively connecting the rack and pinion connection of each carrier bar with said friction rod through said first means, and locking devices for all of said rack and pinion drive connections individually manipulated directly from said main cam shaft. 15
22. In combination with the yarn carrier bars, main friction, and main cam shaft of a full fashioned hosiery knitting machine, actuating mechanism for said carrier bars comprising: a rack connected to each carrier bar, a pinion associated with each rack, a shaft for each pinion, a drive gear loose on each shaft and having a drive connection with said main friction, a clutch device for each drive gear for connecting and disconnecting said drive gear from its associated shaft, a manipulating element for each clutch device, a cam device for each element for the latter's periodic actuation, a ratchet wheel connected to all of said cam devices, a pawl for the operation thereof, link mechanism for operating said pawl, and a cam on said main cam shaft for the direct, periodic operation of said link mechanism. 20
23. In combination with the yarn carrier bars, friction rod, and main cam shaft of a full fashioned hosiery knitting machine, actuating mechanism for said carrier bars comprising: a rack connected to each carrier bar; a pinion associated with each rack bar; a shaft for each pinion; a drive gear loose on each shaft and in permanent gear connection with said friction rod; a clutch device for each drive gear for connecting and disconnecting said drive gear from its associated shaft; a manipulating element for each clutch device; a cam device for each element for the latter's periodic actuation; a ratchet wheel connected to all of said cam devices; a pawl for the operation thereof; link mechanism for operating said pawl; a cam on said main cam shaft for the direct, periodic operation of said link mechanism; an individual brake device for each drive gear; a cam element for the periodic operation of each brake device and directly connected to and associated with said cam devices, to be moved in unison therewith in the operation of said link mechanism. 25
24. Yarn laying mechanism for a straight bar hosiery machine having a main friction comprising a plurality of rotary members, a support therefor secured in a stationary position upon the hosiery machine, a plurality of yarn laying members actuated by the rotary members, reciprocating means having a direct operative connection with the main friction of the hosiery machine for actuating the rotary members, and step-by-step mechanism for controlling the actuation of the rotary members from the reciprocating means to actuate the yarn laying members in repeated sequence. 30
25. In combination with the yarn carrier rods and main friction of a flat hosiery knitting machine, rotary members, means for selectively establishing drive connections between said rotary members and said carrier rods, means travelling with and operated by said main friction for the operation of said rotary members, and individual brake devices associated with each of said rotary members and selectively rendered active and inactive by said means in the operation thereof. 35
26. An attachment for a full fashioned hosiery machine, in combination, a main cam shaft, a main friction, a group of yarn carrier rods, rack bars secured to said carrier rods, a separate gear associated with each rack bar, means operated from said main cam shaft for selectively controlling the operation of each rack bar by its associated gear, and means carried by and directly operated by said main friction and adapted to selectively operate said gears. 40
27. An attachment for a full fashioned hosiery machine, in combination, a main cam shaft, a main friction, a group of yarn carrier rods, rack bars secured to said carrier rods, a separate gear associated with each rack bar, means operated from said main cam shaft for selectively controlling the operation of each rack bar by its associated gear, means carried by and directly operated by said main friction for the selective operation of said gears, and a brake device for each gear and under the control of said cam shaft operated means, whereby each carrier bar, through its associated gear, may be braked at the end of its travel. 45
28. An attachment for a full fashioned hosiery machine, in combination, a power device of the knitting machine, a main friction, a group of yarn carrier rods, rack bars secured to said carrier rods, a separate gear for each rack bar, means operated from said power device of the knitting machine for selectively controlling the operation of each rack bar by its associated gear, means carried by and receiving its power from said main friction for the selective operation of said gears, and a brake device for each gear and under the control of said power device operated means, whereby each carrier bar, through its associated gear, may be braked at the end of its travel. 50
29. In an automatic control mechanism for the movable yarn carrier supporting members of a straight knitting machine, the combination comprising driving means, a plurality of clutch devices for operatively and selectively connecting each of said yarn carrier supporting members to said driving means in driving relation, locking means for said yarn carrier supporting members, 55
30. In an automatic control mechanism for the movable yarn carrier supporting members of a straight knitting machine, the combination comprising driving means, a plurality of clutch devices for operatively and selectively connecting each of said yarn carrier supporting members to said driving means in driving relation, locking means for said yarn carrier supporting members, 60
31. In an automatic control mechanism for the movable yarn carrier supporting members of a straight knitting machine, the combination comprising driving means, a plurality of clutch devices for operatively and selectively connecting each of said yarn carrier supporting members to said driving means in driving relation, locking means for said yarn carrier supporting members, 65
32. In an automatic control mechanism for the movable yarn carrier supporting members of a straight knitting machine, the combination comprising driving means, a plurality of clutch devices for operatively and selectively connecting each of said yarn carrier supporting members to said driving means in driving relation, locking means for said yarn carrier supporting members, 70
33. In an automatic control mechanism for the movable yarn carrier supporting members of a straight knitting machine, the combination comprising driving means, a plurality of clutch devices for operatively and selectively connecting each of said yarn carrier supporting members to said driving means in driving relation, locking means for said yarn carrier supporting members, 75

- a separate control element for each of said devices and locking means, and a single mechanism engaging said control elements to operate the same in a predetermined sequence.
- 5 30. In an automatic yarn-feeding control mechanism for a straight knitting machine having a plurality of movable yarn carrier supporting members, the combination comprising driving means, a plurality of clutch devices for selectively connecting said yarn carrier supporting members and driving means in driving relation, at least
- one locking means for each of said yarn carrier supporting members, a separate control element for each of said devices and locking means, a mechanism having a row of determining elements for each yarn carrier supporting member, each 5 of said rows of determining elements being adapted to engage and operate in predetermined order the control elements for the respective yarn carrier supporting member.

10

JOSEPH L. BEERS.
